BERTIL BRANDER, OF STOCKHOLM, SWEDEN

AUTOMATIC TELEPHONE-EXCHANGE SYSTEM

Application filed August 8, 1925, Serial No. 49,094, and in Sweden May 31, 1924.

This invention refers to an automatic telephone exchange system and particularly to automatic switchboards of a new type for such exchanges in connection with a special 5 calling or number sending device for the subscribers' instruments.

In this system the selectors are carried out in the form of small carriages running on horizontal rails, each carriage or selector being 10 provided with a miniature electric motor, which simply drives the selector along its track forwards and backwards. The connection for the motor current is established by 15 means of a sort of trolley making contact with conductors running along the track. The connections to the various telephone or 20 trunk lines is made by means of a sliding contact arm on the carriage which gets its connections by means of separate rollers and 25 leads along the track in the same way as the motor. The contact arm in its various positions of the selector makes connection with the lines by means of vertical conductors, three for each line, provided with lugs or 30 projections against which three brushes on the contact arm are sliding.

The invention further comprises a number 35 sending device at the subscriber's instrument, especially designed for the cooperation with 40 selectors in this system.

In the accompanying drawings is represented a telephone system according to this 45 invention.

Fig. 1 is a plan, Fig. 2 a front view and 50 Fig. 3 a side view of a selector.

Fig. 4 shows a diagram of the subscriber's 55 instrument. Fig. 5 shows the circuit diagram of a line finder, Fig. 6 the circuit diagram of a group selector and Fig. 7 the circuit diagram of a connector.

Fig. 8 is a diagram of a modified line finder 60 arrangement.

The selector shown in Figs. 1-3 mainly 65 consists of a small three phase motor M, provided with a synchronously rotating armature 35, and arranged to move easily on two small wheels 1, 2 on a rail 5, like a carriage, while it is guided by means of two rollers 3, 4 which engage with a downwardly projecting 70 edge of the carrying rail 6 for the next selector above the one shown in the drawing.

The triangular iron frame 34 of the motor carries the three field coils 33 and the two pole armature 35 is provided with a single coil 39 for polarizing the armature by means 55 of continuous current. The armature 35 is provided with a hollow shaft 36 which revolves on a fixed pin or pivot 37. The shaft 36 carries a pinion 38 engaging with teeth at the front side of the rail 5. The armature 60 coil 39 has one end connected to the body 35 and the other end to an insulated pin 40 at the top end of the armature shaft 36. An insulated spring 41 fixed to the frame 34 presses against the pin 40 and forms one of 65 the connections of the coil 39 to the external circuit, the second connection being formed by the pivot 37 and the frame of the motor.

The motor frame 34 further carries a kind 70 of a trolley, composed of six rollers 13 to 18 insulated from each other and from the frame and making contact with six insulated conductors in the form of rails or strips 19-24. Three of these conducting rails 22, 23, 24 carry the three phase current to the motor 75 magnets 33 while the other three rails 19, 20, 21 form the connection to three insulated brushes 7, 8, 9 mounted on the contact arm K of the selector. The contact arm K is mounted between pivots in a bracket 26 (Fig. 3) 80 fixed to the motor frame 34. The contact arm K is movable a small angle round the pivots, whereby the brushes 7, 8, 9 may be swung out of contact with the multiple bank. This is effected when the selector is moving with 85 its highest speed, by means of a centrifugal device C. This device contains two weights 29, fixed to springs 30, one end of which are fastened to the hollow spindle 28 of the wheel 1, while the other end of the springs 30 are 90 fastened to a pin 31, which moves axially through the spindle 28. Thus the weights 29, when the selector moves very fast, rotate quickly and are thrown outward by the centrifugal force, thereby pressing the pin 31 95 inwards so that the latter will press on the inner end of the contact arm K causing its outer end with the brushes 7, 8, 9 to be swung out from the bank.

The centrifugal device C is however so 100

adjusted that, when the selector moves with a certain slower speed, the pin 31 does not touch the contact arm K, a spiral spring 32 in this case holding the brushes 7, 8, 9 tight 5 up against the bank contacts 10, 11, 12.

The bank or multiple contacts 10, 11, 12 are in the form of metal strips with lugs projecting towards the brushes, as shown in Figs. 1 and 3.

Three of these strips are provided for each 10 line, of which two belong to the talking circuit and the third to the test circuit.

The contact rollers 13—18 are each composed of two pressed halves of thin sheet 15 metal, which are held and pressed together by means of two springs 25, these springs at the same time forming the electrical connection to the rollers. The two halves of the rollers are not in any way fixed together, but 20 each half can revolve freely and it is pivoted in the spring only by means of a pressed up nipple fitting into the hollowness of a similar nipple of the spring 25. These contact rollers engage with the contact rails 19—24 in such 25 a manner that each roller grips the rail tightly between its two halves, thus forming a reliable (double) contact with only slight wear of rubbing surfaces.

From the foregoing description of the selector 30 it will be understood that, properly speaking, the selector is composed of two main parts, namely the fixed track with its rails, and the carriage or selector proper which acts as a sliding contact arm. In the following 35 description of the operation of the system, however, the movable carriage, for sake of shortness, is called the selector.

It is obvious, that the line capacity of this selector may be varied within wide limits, 40 because the construction of the movable part of the selector is of course not in any way depending on the length of the track. Thus, this selector may be made for any desired 45 number of lines, for instance 100—1000 lines, provided that the carriage is arranged to run fast enough, so that the switching operation can be completed in a reasonable time. For this reason, if the selector is arranged for a 50 large capacity, for instance 500—1000 lines, it is given a faster motion when selecting groups, for instance 100—150 steps per second—one step expressing the distance the selector must move from one set of multiple 55 contacts to the next set—while for the selection of an individual line in the groups a speed of only 30—40 steps per second may be used. To avoid excessive wear of the sliding brushes and multiple contacts during the faster motion of the selector, the above mentioned centrifugal device C holds the brushes 60 out of contact with the individual lines during the faster motion.

The operation of the selector will be clearly understood from the following description 65 of the circuit diagrams, which represent the

switches of an automatic exchange for 10000 subscribers' lines. The capacity of the line 70 finder, Fig. 5, may be 500—1000 lines and the group selector, Fig. 6, 500 lines—10 groups of 50 lines. The capacity of the connector in consequence will be 1000 subscribers' lines.

Fig. 4 shows the diagram of the subscriber's instrument A including the number sender.

The circuits for talking and ringing in this 75 instrument may be of any kind generally used for common battery working.

The number sender consists mainly of a switch arm 50 in connection with a spring driven wheel-work.

The switch arm 50 is fixed to a toothed 80 wheel 56 and a clock spring 60 has one end fixed to this wheel 56 and the other end to a crank 61 for winding up the spring. The wheel 56 engages with the pinion of a second wheel 57 engaging with a pinion 58 on the 85 shaft of a thin, blade-shaped steel magnet N—S mounted on pivots between the poles of an electro-magnet 59 so that it may freely rotate when the electromagnet 59 is not energized. The switch arm 50 normally rests on a contact 55 and in this position it closes the 90 circuit of the speaking set A across the branches 65, 66 of the subscriber's line, but when the arm 50 is set in rotation by turning the crank 61 one turn round, it leaves the contact 55, thereby interrupting the circuit of the speaking set A, and then slides successively over four contact segments 51, 52, 53, 54 and then stops again, after one revolution, 95 on the normal contact 55.

The contact segments 51—54 are arranged 100 in such a manner, that their active contact surface may be individually varied to different lengths by means of a turning knob or any kind of a handle moving over a scale 105 with the divisions marked with numerals or letters according to the adopting numbering scheme. To effect the variation of the active contact surface of the segments 51—54, these segments may have a concentric movement, 110 whereby they will be more or less covered by fixed insulating segments of some thin material.

Fig. 5 is a diagram showing the relays in connection with the subscriber's line in the 115 central exchange and the circuit of a line 120 finder.

The subscriber's line 65, 66 is connected to contacts 67, 68 in the multiple contact field of the line finder and one branch 65 is further connected to one winding of a combined line and cut off relay 70 and a pilot relay 71, which is connected to the earthed plus pole of the central battery, while the other branch 66 is connected to the minus pole of the battery through a resistance 72. The corresponding test contact 69 in the multiple field is connected to a contact 73 of the line relay 70, which when energized extends this circuit to the minus pole of the battery through a sec- 125 130

ond winding of the relay 70. This relay is adjusted in such a manner that its armature only closes the contact 73 when it is excited only by the current in the line and its left hand winding, which has a high resistance; but when a local circuit is closed through its right hand low resistance winding, it becomes more powerfully excited and then also opens the two other contacts, thus cutting itself and the battery off the line.

10 The pilot relay 71 is common to a certain number, for instance 100 lines, and its purpose is, by the aid of a secondary pilot relay 74, to start a number of line finders provided for the groups of lines in question.

15 The line finder differs mechanically from the selector shown in Figs. 1-3 with regard to the centrifugal device C, Fig. 1, which is omitted in the line finder, because the latter is arranged in such a way that it has no definite normal position but simply stops at the contacts where it was lastly used. It is therefore not necessary to give the line finder the high speed, as there will always be some line finders in the neighbourhood of the calling line. On the other hand, the line finder is provided with a switch 80, Fig. 5, which is actuated by means of a fixed stop or projection at each end of the track in such a manner that it changes its position every time the line finder reaches one end of the track, whereby two phases of the three phase current are changed, causing the motion of the motor to be reversed.

20 According to the diagrams shown in Figs. 4-7, which of course only serve as an example of a suitable way of carrying out the invention, the operations of the line finder and the group selector are controlled only by means of relays, while for the operation of the final selector a sequence switch is used in conjunction with some relays.

25 To facilitate the understanding of the diagrams and the operation of the switches a short explanation of the method of handling the subscriber's instrument and the number sender may be advanced, particularly because this method somewhat deviates from the ordinary course.

30 1. The subscriber sets the desired number by turning the contact segments of the number sender in accordance with the figures of the number, then he starts the number sender by turning the crank once round, all while the receiver remains in its resting position.

35 2. As soon as the number sender has been started, the subscriber may remove the receiver from its support and wait for the usual tone signal in the receiver, indicating either that the wanted number is being rung up or that it is engaged. But if the subscriber prefers it, he need not immediately remove the receiver but he may wait till the bell rings, which is a sign that the connection to the desired line is completed and that the line is

not busy, and when he now lifts the receiver the wanted subscriber will be called. If the wanted number is engaged, however, he does not get the ring back, and in this case he need not trouble himself with the instrument and waste his time in waiting for a tone signal. In the latter case the whole chain of switches, used for setting up the connection, after a few seconds are automatically restored to their normal positions.

40 3. In order to renew a call it is, of course, only necessary for the subscriber to again wind the spring of the number sender.

The operation of the system is as follows:

45 Supposing a subscriber wants to call No. 5280. He sets the number sender accordingly, and the contact segments 51-54, Fig. 4, will then have the positions or proportionate lengths shown in the figure. Next he turns the crank 61 once round, thereby winding the spring 60, at the same time releasing the switch arm 50, which leaves the normal contact 55 and passes over to the segment 51. (The mechanical details of the release and interlocking arrangement of the switch arm 50 and the crank 61 will be the subject of a separate patent application.) Meanwhile the armature N-S revolves freely, only acting as a mechanical brake, because there is no current flowing through the windings of the electromagnet 59. But as soon as the switch arm 50 reaches the segment 51 a current is closed through the electromagnet 59 which now retains its armature and stops the motion of the switch arm 50. The circuit of this current is: plus pole of the central battery (earth)-71-70-65-50-51-59-66-72-minus pole. This current energizes the line relay 70, which closes the contact 73 (but does not yet open its breaking contacts), thereby connecting the multiple test contact 69 to the minus pole through the right hand winding of relay 70.

50 At the same time relay 71 closes a local circuit for relay 74, which sets earth on a bus bar 82, from which branching wires 83 lead to the starting relays 81 of a number of line finders. All those relays 81, which belong to vacant line finders, will thus be energized. Circuit of each start relay 81: Earth-75-110-83-81-85-minus pole.

55 The relay 81 closes, by means of its contacts 87, 88, 89, the three phase current from a generator G over the winding of three polarized relays 95, 96, 97, the normally closed contacts of a test relay 82 and the field coils 91, 92, 93 of the motor M. At the same time a continuous current is closed through the armature coil 94 from the battery B. Further relay 81 puts earth potential on the test brush 98 over the contact 90 and the test relay 82.

60 Thus all vacant line finders, provided for the group of lines in question, are started and the one, whose test brush 98 first comes in 120 contact with the normally closed contact 90, 125

- contact with the test contact 69 of the calling line, will stop on this line, because the test relay 82 will be energized in series with the cut off winding of the relay 70. As this relay winding has a comparatively low resistance the relay 70 will at the same time be more powerfully excited and will therefore pull up its armature fully, breaking the two normally closed contacts.
- 10 The test relay 82 being energized cuts off the three phase current to the motor M, but at the same time it closes a direct current through one (or two) of the field coils 91, 92, 93 in series with the armature coil 94 and the left winding of the relay 84. This current is taken from the central battery, which has a higher voltage than the generator G and the battery B, and as the said winding of the relay 84 has a low resistance, it will be stronger than the currents for driving the motor. It has however only a short duration, as will be further explained below, the purpose of this current being only to stop the motion of the motor armature as quickly as possible and 20 to pull it back in such a position that the brushes of the contact arm K will coincide properly with the multiple contacts 67, 68, 69 of the calling line.
- 25 The adjustment of the position of the line finder with its contact arm K in relation to the multiple field contacts 67, 68, 69 is effected by means of the motor and the polarized relays 95, 96, 97, which during the working of the motor M vibrate in synchronism with the alternating currents. When these currents are interrupted, the armatures of the polarized relays 95, 96, 97 remain in the positions they had just in the breaking moment and in consequence one or two of their contacts 102, 103, 104 will remain closed after the break of the three phase current. It is thus obvious that the continuous current from the central battery will be closed over one or two of the contacts 102, 103, 104 in series with the corresponding contact or contacts of the three closed contacts 99, 100, 101 of the test relay 82 and the left winding of the relay 84, and this current (or these currents) will excite the field and armature coils 30 of the motor M in such a manner that the armature will take up the same position it had in the moment the three phase current was broken. The relay 84 is consequently energized at the same time and by opening its contact 85 it cuts off the current for the start relay 81. The latter relay is however arranged with a slow acting release, so that it keeps its contacts 87, 88, 89, 90 closed a short time—for instance half a second—after the 35 opening of the contact 85, and during that interval the setting of the motor armature, effecting the adjustment of the contact arm K on the field contacts, is completed.
- 40 The relay 84, when energized, also closes three contacts 86, 105, 106 by which the con-

ductors 107, 108, 109 leading from the three brushes of the contact arm K are extended to the group selector, Fig. 6. At the same time a new circuit is formed for holding the relays 70 and 84: earth—a resistance 110 (Fig. 6)—70—84—86—109—98—69—73—70—minus pole. When subsequently relay 81 releases its armature and opens its contacts, this does not interfere with the holding of the relays 70 and 84, but by the release of the relay 82, which follows on the opening of the contact 90, the setting current in the motor coils is broken.

45 At the above mentioned closing of the relay contacts 105, 106 a new line circuit is formed at the moment of cutting out the line relay 70 from the subscriber's line, through the winding of a starting relay 117 for the group selector as follows: central point of the common battery CB (Fig. 6)—111—105—107—67—65—50—51—59—66—68—108—106—112—117—CB, minus pole. Thus the electro-magnet 59 of the number sender remains excited, still retarding the wheel work, but the starting relay 117 is now also energized. This relay closes by the contact 118 the circuit of a relay 119, which by its contacts 120, 121, 122 closes the three phase current to the motor M of the group selector. This three phase current is however not taken from the generator G, Fig. 5, but from another generator, supplying a current of a higher frequency, say 20-30 periods per second, while the generator G may give a current of only 5-10 periods.

50 The battery B, Fig. 5, is also connected to the central point of the winding of the generator for the higher frequency.

55 Thus the armature coil 123 of the group selector motor M is polarized by the continuous current in the same way as the armature of the line finder motor and will rotate in synchronism with the phase. On account of the high speed of the motor the centrifugal device (Fig. 1), which is provided in this selector, will come into action and turn the brushes 124, 125, 126 of the contact arm K out of contact with the multiple. One of the brushes, 126, will however during the faster motion of the selector slide on a number of special, earthed contacts 130, which are standing out of the surface formed by the multiple contacts and may have an extended contact surface as indicated in Fig. 6. These contacts 130 are provided for the purpose of sending an impulse to the number sender every time the selector passes into a group of trunk lines. Thus there will be 10 impulse contacts 130 for each group selector track, as in the example there are 10 groups of trunk lines leading to final selectors.

60 When the group selector leaves its normal position a switch 131 is released, which closes two contacts 132, 133 as a preparation for subsequent functions.

65 When the brush 126 during the motion of

the group selector comes in contact with the earthed contact 130, the earthed plus pole of the central battery CB is directly connected to one branch of the subscriber's line by the closed contact 134 of the starting relay 117, which results in the following line circuit: earth—130—126—134—112—106—108—68—66—59—51—50—65—67—107—105—111—CB (central point). In consequence the current in the subscriber's line is reversed when the brush 126 touches the contact 130, but is restored to its original direction again as soon as the brush 126 leaves the contact 130.

As the electro-magnet 59, Fig. 4, will allow its armature N—S to make one half revolution for every reversal of the line current—which movement is due to the driving spring but is also supported and accelerated by the motoric effect of the pole change of the magnet 59—the armature N—S will perform a full revolution every time the contact arm K, Fig. 6, of the group selector passes a contact 130, that is to say, every time the selector arrives to a fresh group of trunk lines. The gearing of the wheel-work, Fig. 4, is carried out in such a manner that the switch arm 50 moves one step—corresponding to one unit of every figure in the recorded number—for every complete revolution of the armature N—S. Thus, when the group selector has passed five groups of lines, the switch arm 50 of the number sender will stand at the bottom of the segment 51 and when the group selector enters the sixth group, the switch arm 50 will leave this segment and break the current in the line and the magnet 59. In consequence the wheel work will no more be retarded by the magnet, but the switch arm is moved on by the driving spring, while the armature N—S again acts as a mechanical brake, until the switch arm 50 comes in contact with the next segment 52, whereby the line current is again closed through the magnet 59. During this momentary interruption of the line current, the relay 117, Fig. 6, releases its armature and short circuits by its normally closed contact 135 and the previously closed contact 132 of the "off normal" switch 131 its own winding, which short circuit prevents the relay 117 to come into action again until the selector has returned to zero. The line current is thus (somewhat increased in strength) again closed through the magnet 59, Fig. 4, as soon as the switch arm 50 reaches the segment 52, as already mentioned, whereby the wheel work is again retarded by the magnet 59.

By the release of the relay 117, Fig. 6, its contacts 118 and 134 are opened, the former opening the circuit of the relay 119, which in turn opens its contacts 120, 121, 122 and cuts off the three phase current of the higher frequency from the motor M of the selector, while the latter contact 134 cuts off the connection between the relay 117 and the brush

126. At the same time a current is closed from earth by the contact 136, the previously closed contact 133 of the "off normal" switch 131 and the normally closed contact 140 of a relay 139 through the winding of a relay 137, which is further connected to the minus pole by a normally closed contact 141 of a relay 138. It will be noticed that the winding of the relay 138 is at this moment connected in parallel with the relay 137, but as the latter relay has a winding of a lower resistance, giving considerably more ampere-turns, than the winding of the relay 138, it will pull up its armature much quicker than the relay 138, which in consequence will be cut out by the contact 142, before it has had time to pull up its armature.

The relay 137 closes by its contacts 143, 144, 145 three phase current of the lower frequency from the generator G, Fig. 5, to the motor M of the group selector, which now will continue its motion at a reduced speed over the multiple contacts of the sixth group. Owing to the lower speed of the selector, the centrifugal device C, Fig. 1, will in this case not have any influence on the position of the contact arm K and its brushes, which in consequence will slide on all the multiple contacts 127, 128, 129 of the group.

The three phase current of the lower frequency, as in the case of the line finder, is passing through the windings of three polarized relays 147, 148, 149 for the adjustment of the position of the selector when stopped.

The relay 137, when excited, connects by the contact 146 the test brush 126 of the selector with the minus pole of the battery through the right winding of the test relay 139 and a resistance 155. When the test brush 126 makes contact with the test contact 129 of a vacant trunk line, the test relay 139 will become excited and will break the supply of three phase current at the contacts 150, 151, 152, at the same time connecting the windings of the motor M to the contacts of the polarized relays 147, 148, 149, cutting off the current to the relay 137 at the contact 140 and earthing the resistance 110 by the contact 153, which substitutes this earth connection for the normally closed contact 113 of the relay 116 when this relay, a moment later, pulls up its armature. The circuit of the test relay 139 is traced as follows: earth-contact 164 of the sequence switch of the final selector, Fig. 7,—resistance 163—162—129—126—139—155—146—minus pole.

When the three phase current is cut off by the test relay 139, the polarized relays 147, 148, 149 will retain their armature in the positions they had at the breaking moment and by the one or two of its contacts, which thus remain closed, battery current will flow through the motor coils and adjust the position of the selector in the same manner as described with regard to the line finders. The

said battery current also passes the winding of the relay 116, but this winding is for a moment shunted by the left winding of the relay 139, which has only a low resistance, and for this reason the relay 116 can not at once pull up its armature. The cause of the left winding of the test relay 139 remaining for a short time as a shunt of the relay 116 is mainly that the relay 137 is arranged for a sluggish release (in some well known manner), otherwise the contact 142 would have been closed, the relay 138 excited and the contact 154 broken, cutting out said shunt, almost simultaneously with the break of the contact 140 of the test relay 139, but by the slow release of the relay 137 the shunt will remain in circuit say one half second, which is sufficient for the adjustment of the selector brushes to their proper position on the multiple contacts. After that interval the above mentioned change in the relay circuits will take place. The said shunt is carried out as a winding of the test relay 139 for the purpose of holding the relay in case the motor no sooner can be stopped than the brush 126 has left the test contact 129 and then is brought back again by the adjusting current. If the multiple contacts and the gearing of the motor arranged in such a manner that one revolution of the motor armature carries the selector six steps along the track, it is evidently possible to bring the selector nearly three steps back if it should be necessary, because the adjusting current can turn the motor armature half a revolution backwards when stopping the motor.

By cutting out the shunt of the relay 116 the current in this relay, which has a high resistance, will be as much increased that the relay will pull up its armature, thereby disconnecting the line from the battery CB at the contacts 111, 112 and extending the line circuit, by closing the contacts 114, 115 to the brushes 124, 125 and further to the connector, Fig. 7. The relay 116 also opens the contact 113, which however has no immediate influence on the circuits, because this contact is bridged by the contact 153 so long as the test relay 139 remains active, but it will serve to release the line finder when the test relay 139, at the end of the conversation, is cut out by a break of its circuit at the connector.

When the relay 138 is energized it closes a contact 156 for holding the relay 139 in place of the contact 146 and at the same time to increase the minus potential of the multiple test contacts 129 by cutting out the resistance 155. The contacts 154 and 156 are arranged in such a way that 156 is closed before 154 is opened, in order to prevent the relay 139 from falling back through any momentary break of the holding current.

The principal function of the relay 138 is to restore the group selector to its normal position after the conversation, or if the desired

line is engaged. For this purpose it closes three contacts 157, 158, 159, by which three phase current of the higher frequency flows to the motor when the test relay 139 is released, and closes its contacts 150, 151, 152. It will be noticed that, in this case, two leads for the phase current are exchanged, in order to reverse the motor and drive the selector backwards to its normal position. Having reached its normal position, the selector strikes against the switch 131, which opens its contacts 132 and 133, the latter contact breaking the holding circuit of the relay 138.

For the connector, Fig. 7, there is provided a sequence switch, which in conjunction with some relays is used for controlling the movements of the connector and other operations in connection with same.

The design of the sequence switch is quite optional. It may be of the well known power driven type or it may have an ordinary step-by-step drive. In Fig. 7 the driving mechanism of the sequence switch is represented by an electro-magnet 168, and for the understanding of the circuits and operations it is sufficient to presume that all the switch arms of the sequence switch are moving simultaneously and with a constant speed, as soon as the magnet 168 is energized. The numerals at the switch arm contacts indicate the positions in which the respective contacts are closed.

For sake of shortness the sequence switch is in the following description called only "switch" and the sequence switch arms only "switch arms".

In the example of the system, represented in the drawings, the connector has a field of multiple contacts for one thousand subscribers' lines, which are divided in ten groups of a hundred lines, while each of the 100-line groups is again divided in ten groups of ten lines each. It is obvious that the connector may be carried out for some other capacity for instance 500 lines, in which case the length of the connector track of course is reduced to one half of the track for 1000 lines.

When the group selector, Fig. 6, has found a vacant connector, Fig. 7, the subscriber's line is with one branch 160 connected to the central point of the common battery, in Fig. 7 indicated with $\mp$, and with the other branch 161 to the minus pole of the battery through a starting relay 167, as in the case of the group selector. The line circuit is then as follows: 165—160—127—124—114—105—107—67—65—50—52—59—66—68—108—106—115—125—128—161—166—167—minus pole of battery.

The starting relay 167, in consequence, is energized and closes by its contact 169 a current to the switch magnet 168. Circuit: earth—169—170—168—minus pole of battery. Thus the switch starts moving all its switch arms, but when they arrive to posi-

tion 1, the arm 170 breaks the circuit of the magnet 168 and the switch stops in this position. The relay 167 has further closed three contacts 171, 172, 173 and by these contacts and the switch arms 174, 175, 176 three phase current of the higher frequency is closed to the motor M of the final selector from the supply circuit X, Y, Z.

During the fast motion of the connector the contact arm K with its brushes 177, 178, 179 is turned out of contact with the multiple contacts 180, 181, 182 of the lines in the same manner as described with regard to the group selector, but the test brush 179 slides on two kinds of impulse contacts, namely one contact 183 at the beginning of every group of hundred lines, which is connected to the minus pole of the battery, and one contact 184 at the beginning of every group of ten lines, which is connected to earth. The test brush 179 is connected to a relay 185, which by the switch arm 186 in the position 1 is connected to earth.

When the connector starts and enters the first group of lines, the brush 179 will make contact with the first impulse contact 183 and close the circuit of the relay 185, which closes a contact 187, thereby earthing one branch 161 of the line. This will cause a reversal of the line current in the same way as described with reference to the group selector, while the starting relay 167 remains energized. Owing to the reversal of the line current the magnet 59 of the number sender, Fig. 4, will change its poles, its armature will make half a turn and the switched arm 50 will move half a step forward on the segment 52. The line current is again reversed when the brush 179 leaves the impulse contact 183 and the switch arm moves another half step. The brush 179 then slides over all the earthed impulse contacts 184 for the decades, but this has no influence on the relay 185, because it is still connected to earth by the switch arm 186. The same procedure is repeated when the connector enters the second group of hundred lines, the switch arm 50 then moving another step. But when the connector enters the third hundred a momentary break of the line current takes place while the switch arm 50 is going over from the segment 52 to 53, and this causes the relay 167 to release its armature for a moment. During this interval the three phase current is cut off at the relay contacts 171, 172, 173, the continuous current is closed through the motor coils by the contacts 189, 190, 191—in this case not for the purpose of adjusting the position of the selector but only to act as a brake on the motor—and a current is sent through the switch magnet 168 by the contact 188 and the switch arm 170, driving the switch in the position 2. The switch arm 170, in moving to the position 2, again breaks the circuit of

the magnet 168, but when the relay 167 at the arrival of the switch arm 50 to the segment 53 is again excited, it closes the same three phase circuit again and also the circuit of the switch magnet 168 by the contact 169 and the switch arm 170, driving the switch in the position 3. The current for braking the motor passes through a differentially wound relay 200, the function of which will be explained below.

The connector now continues its motion forward, but when the switch moved from position 1 to 2, the impulse relay 185 was switched over from earth to the minus pole of the battery by the switch arm 186, the latter connection remaining also in the position 3 of the switch.

When subsequently the brush 179 of the contact arm K passes the impulse contacts 184, the relay 185 will receive an impulse for each of the contacts 184 passed by the brush and this will result in as many impulses being sent to the number sender in the same way as described before. According to the example of the number recorded in the number sender, the switch arm 50 will thus move nine steps by the decade impulses and, at the ninth step, it will leave the segment 53 and again break the line current. The starting relay 167, which is deenergized during the time the switch arm 50 is passing between the segments 53 and 54, cuts off the three phase current, closes the braking current, as before, and sends a current to the switch magnet 168, whereby the switch is moved from position 3 to 4. The switch arms 174, 175, 176, when moving to position 4, disconnect the relay contacts 171, 172, 173 from the three phase supply circuit X, Y, Z, and at the same time the relay 185 is switched over from the minus pole of the battery to its central point—marked $\pm$, by means of the switch arm 186.

The starting relay 167 is again excited, as soon as the switch arm 50 of the number sender has reached the segment 54, and the relay contacts 171, 172, 173 are thus again closed, but the motor M does not receive the driving current again, before the switch arms 174, 175, 176 arrive in position 5. In the meantime the closing of the relay contact 169 puts earth on the branch 161 of the line, causing the line current to be reversed and the switch arm 50 of the number sender to move half a step. Further when the braking current the last time is closed to the motor by the relay contacts 189, 190 or 191 via the switch arms 192, 193 or 194 and the relay contacts 195, 196 or 197, this current passes through the differentially wound relay 200 and excites this relay—in a way explained below—so that it opens its contact 216, and when the relay 167, as already mentioned, is again excited, interrupting the braking current at the contacts 189, 190, 191,

the relay 200 is (slowly) released and closes a current by its contact 216 via the switch arm 215 to the switch magnet 168 causing the switch to move to position 5. In doing so, the switch arm 246 breaks the earth connection via the relay contact 169, causing the switch arm 50 of the number sender to move another half step.

It will be understood that the arrangement of the switch arm 246 in connection with the relay contact 169 serves to send an extra impulse to the number sender on account of the fact that the connector stops on the line following the opening of the line circuit when the switch arm 50 leaves the segment 54. At the same time the switch arms 174, 175, 176 in position 5 close the low frequency three phase current to the motor M via the windings of the polarized relays 201, 202, 203, and the connector, which has now arrived to the ninth group of tens within the third hundred, continues its motion at a slower speed, while the brushes 177, 178, 179—not being influenced by the centrifugal device C—slide on the multiple contacts 180, 181, 182.

During this motion of the connector the relay 185 will receive an impulse every time the test brush 179 passes over a test contact 182. The connection of the relay 185 to the central point of the common battery during this last motion of the connector is done to enable the relay 185 to receive the impulses from the test circuit of every passed subscriber's line without regard to whether the line is busy or not. If the passed line is free, its test contact 182 has a minus potential through the right winding of the line relay 70, Fig. 5, in which case the impulse circuit will be: $\mp$ —186—185—179—182—204—70—minus pole of battery. If a line is busy, its test contacts 182 are connected not only with the minus pole, as before said, but also, through a test relay, with the plus pole of the battery according to the, already in connection with the line finder described and well known, method of testing and marking a line busy. As the test relay 167 (right winding) has a low resistance, the test contact 182 of a busy line will have plus potential. The impulse circuit when passing a busy line will therefore practically be as follows: earth—169 (or 208)—207—167 (right winding)—179—182 (the preceding parts exist at the connector occupying the busy line, while the following parts are found at the moving connector)—182—179—185—186— $\mp$.

In order to prevent these impulses from influencing in any way the line relay 70 or the test relay 167, connected to a passed busy line, the impulse relay 185 is provided with winding of high resistance, for instance 2000—3000 ohms.

When the connector has passed nine lines of the ninth group of tens, the number send-

er has received ten impulses since the switch arm 50 arrived to the segment 54, and at the tenth impulse the switch arm 50 leaves the segment 54, interrupting the line circuit and continuing its motion by the force of the spring 60 until it arrives to its zero position, where it connects the subscriber's speaking set A with the line by the contact 55.

At the last interruption of the line circuit by the switch arm 50, the relay 167 is released and by opening its contacts 171, 172, 173 it cuts off the three phase current and by closing its contacts 189, 190, 191 sends the adjusting current through the motor coils. This current flows from earth through the armature coil 209 of the motor M, the field coil or field coils of same, which by one or two of the contacts 195, 196, 197 remain in the circuit at the moment the three phase current is cut off, the winding 210 of the relay 200, shunted by the winding 211 in series with a resistance 213, to the minus pole of the battery. It will be understood that the winding 210 of the differentially wound relay 200 is in this case the active winding, the resistance 213 being very high compared with the resistance of the relay windings 210, 211, which are equal with regard to resistance and number of turns. The relay 200 closes its contact 214, thereby sending a current to the switch magnet 168 over the switch arm 215. Thus the switch moves to position 6, the said current being broken in this position by the switch arm 215.

The switch arms 192, 193, 194 at the same time cut off the adjusting current for the motor, but a switch arm 199 in moving to position 6 serves to substitute the broken earth connection for the circuit of the relay 200 by a resistance 198, so that the energization of the relay 200 is continued in position 6 of the switch.

The relay 200 is provided mainly to serve as a time relay, which function begins in the position 6 of the switch. For this purpose the resistance 212 is carried out in the form of a very fine wire of copper or some other material with a high temperature coefficient of resistance and arranged in such a manner that it will not be damaged by being heated to a temperature of 70° — 80° C. Further it is arranged for cooling quickly by the surrounding air, as soon as it is not heated by current. The ohmic resistance of 212 is at a temperature of 15° to 20° C. somewhat lower than that of the resistance 213, which is made of ordinary resistance material, not changing its ohmic resistance perceptibly when heated. Or the resistance 213 may consist of any material, if it is only arranged in such a manner that it is not heated materially by the current passing it. The ohmic resistance of 212 at ordinary temperature may be, for example, 900 ohms while 120

the resistance 213 measures 1000 ohms and each winding 210, 211 of the relay 200 about 100 ohms.

The relay 200 begins to act as a time relay when the switch arm 199, in going from position 5 to 6 opens a short circuit of the resistance 212 and connects the resistances 212, 213 to earth through the resistance 198, the purpose of the latter resistance being only to regulate the time required for heating the resistance 212.

On account of the difference in the ohmic resistance of 212 and 213 the current in the relay winding 210 will be about 10% stronger than in the counteracting winding 211, and this difference is sufficient for retaining the armature of the relay. The temperature of the resistance 212 will now gradually rise and after, for instance, 10 seconds its resistance has increased to about 1000 ohms. In consequence the relay 200 is demagnetized and its armature falls back.

When the switch moves from the position 5 to 6 it further performs the following changes in the various circuits:

1. The starting relay 167 is disconnected from the line by the switch arm 166 and the right winding of relay 167, which is connected to the test brush on one side, is on the other side connected to earth by the switch arm 207 through a resistance 208, for the purpose of converting the starting relay 167 to a test relay.

2. The switch arm 170 connects the switch magnet 168 to the relay contact 169 of the test relay 167.

3. The switch arm 215 changes the connection of the switch magnet 168 from the relay contact 214 to the contact 216.

4. The switch arm 165 changes the connection of the line branch 160 from the central point of the battery to the earthed left winding of an inductance coil 217.

5. The switch arm 166, when disconnecting the line branch 161 from the relay 167, connects said line branch 161 to the windings of the clearing relay 220 for the calling subscriber.

6. The switch arm 218 connects the earthed right winding of the inductance coil 217 to a tone generator 219.

The connector is now standing on the multiple contacts 180, 181, 182 of the desired subscriber's line No. 5280 and the next operation is to test whether this line is busy or not. This is done by the relay 167 on the well known principle that the test relay, when connected in series with the cut off relay of the desired subscriber's line, will be sufficiently energized to pull up its armature simultaneously with the cut off relay coming into action, if the line is free, while, if the line is busy, the test relay can not pull up its armature, because it is shunted by another test relay.

If the line is busy, then the following functions take place:

The test relay 167 remains inactive and the time relay 200 keeps its armature attracted for about 10 seconds after the switch has arrived to the position 6, as already mentioned above. During this interval a busy tone is transferred to the calling subscriber's line from the tone generator 219 by means of the coil 217. As mentioned above, the subscriber may now listen in his receiver and observe the busy tone, if he chooses to do so, or he may still leave the receiver on its support, the lifting of the receiver being of no influence on the switching operations when the desired line is busy.

When the line relay 200 becomes deenergized by the heating effect of the current in the resistance 212, its armature falls back and closes the contact 216, thereby sending a current through the switch magnet 168 and driving the switch to the position 7, where it stops owing to the said current being broken by the switch arm 215. When going from position 6 to 7 the switch arm 164 breaks the direct earth connection to the resistance 163 and connects this resistance to earth over the contact 225 of the "off normal" switch 222, which closed the contact 225 when the connector left its position of rest.

The switch arms 192, 193, 194, having arrived to the position 7, close the three phase current of the higher frequency to the motor M, but in this case two of the phases (Z, Y) are changed and, in consequence, the motion of the motor is reversed and the connector returns home. Having reached its home position the connector stops against the "off normal" switch 222, which goes back to the position shown in the drawing, thereby changing the earth connection from the contact 225 to the contact 224. This opens the holding circuit for the group selector, which will return to its home position as described in connection with the group selector.

At the same time the closing of the contact 224 sends a current over the switch arm 223 through the switch magnet 168, driving the switch to position 8. From this position it is brought to position 9 by the closed contact 216 of the relay 200 and the switch arm 215; from position 9 it is brought to position 10 by the closed contact 226 of the relay 220 and the switch arm 223, further to position 11 by the closed contact 233 of the relay 230 and the same switch arm 223 and at last it is brought to its normal position 0 by the closed contact 224 and the switch arm 223.

It is thus obvious that, when the desired number is engaged, the connector, the group selector and the line finder all return to normal without any possibility of being kept engaged any longer by the subscriber.

If the desired line is free, the following functions take place:

As soon as the switch arrives to the position 6, the test relay 167 is energized in series with the line and cut off relay 70 of the wanted line, both these relays pulling up their armatures simultaneously. At the closing of the relay contact 169 the switch is now at once moved to the position 7 by a current passing said relay contact 169 and the switch arm 170. When going to position 7 the switch arm 207 cuts out the resistance 208 from the test circuit and connects the right winding of the test relay 167 to its own closed contact 169 for holding. But the switch does not stop in the position 7, because the relay 200 is still energized by the current passing the resistance 198 and the switch arm 199, thus the switch magnet 168 receives a current by the contact 214 and the switch arm 215, driving it to the position 8. In this position the switch arm 199 has changed the earth connection for the time relay 200 from the resistance 198 to direct earth over the closed contact 169 of the relay 167, and in consequence the resistance 212 now receives a stronger current and will therefore in a shorter time be heated to the temperature, at which the relay 200 releases its armature, the strength of the current being so adjusted that the said time will be $1\frac{1}{2}$ to 2 seconds. During this time an uninterrupted first ringing signal is sent out from the ringing machine 240 by the switch arm 239. This ringing signal is however to begin with, sent out only over the calling subscriber's line, if this subscriber has not previously taken his receiver from its support, and only when this is done, is said signal changed over to the wanted subscriber's line. This operation is performed by the relay 220, which is energized by the transmitter current in the subscriber's instrument. A condenser 246, inserted in series with the ringing machine prevents continuous current coming through the machine. The circuit of the said ringing current, in case the calling subscriber has not yet taken off his receiver is as follows: 240—246—239—228—220 (right winding)—166—161—128—125—115—106—108—68—66—A (the bell and condenser)—55—50—65—67—107—105—114—124—128—160—165—217 (left winding)—earth—240. It will be observed that this ringing current is partly shunted by the left winding of the relay 220 in series with the inductance coil 221, but the effect of the current passing this shunt is counteracted and practically neutralized by the main current passing the right winding of the relay 220. The two windings may have about the same number of turns, or the right winding may have fewer turns, depending on the inductance of the coil 221. Of course the main current in this winding will vary a little according to the resistance of the subscriber's line, but this variation, owing to the high resistance of the

condenser in series with the bell of the instrument, will be comparatively small and of no influence on the relay, which will remain inactive during the ringing until the subscriber takes the receiver off. When this is done, the battery current is closed through the subscriber's transmitter and this current flows through the left winding of the relay 220, which now attracts its armature. At the closing of the transmitter circuit the ringing current in the right winding of the relay 220 is for a moment increased, which also contributes to the energization of the relay. By opening its contact 228 and closing 229 the ringing current is now switched over from the calling to the called subscriber's line, passing a normally closed contact 231 of the called subscriber's clearing relay 230 and the left winding of this relay, which neutralizes the effect of the portion of the current, shunted by the right winding and the inductance coil 235 in exactly the same manner as when the ringing current went out to the calling subscriber over the relay 220.

The circuit of the ringing current to the called subscriber is as follows: 240—246—239—229—231—230 (left winding)—238—178—181—205—A (bell and condenser of the called subscriber's instrument)—206—180—177—237—217 (right winding)—earth—240.

This ringing current, in passing the right winding of the coil 217, produces by induction a similar, fainter current in the left winding of the coil 217, which flows through the receiver of the calling subscriber as a control signal of the ringing up of the called subscriber.

If the called subscriber does not at once answer, this first ringing to the calling and the called subscribers will last altogether about 2 seconds, as mentioned above; after that time the time relay 200 will release its armature and send a current to the switch magnet 168 by the contact 216 and the switch arm 215, driving the switch to the position 9. In this position the switch arm 239 has cut the direct connection between the ringing machine 240 and the called line, and connected said line to an interrupter 241 for periodical ringing. At the same time the switch arm 199 has cut out the line relay 200, as it is not required any more for the present connection. The periodical ringing is now continued until either the called subscriber answers or the calling subscriber replaces his receiver.

When the called subscriber answers, his clearing relay 230 is energized in exactly the same manner as the clearing relay 220 of the calling subscriber. When the relay 230 pulls up its armature, the ringing current is cut off by the contact 231 and a current set to the switch magnet 168 by the contact 234 and the switch arm 227, driving the switch from posi-

tion 8—if he answers while the first ringing current was sent out—or from position 9—if he answers during the periodical ringing—to position 10, which is the speaking position. In this position the switch arm 239 has cut off the ringing machine from the relay contacts, the switch arms 242, 243 complete the connection between the subscriber's line and the switch arm 237 has connected the branch 206 of the called subscriber's line to an inductance coil 236, forming the counterpart of the coil 235 for the supply of battery current to the transmitter of the called subscriber. Two resistances 244, 245 are inserted in the branches between the subscribers' lines, in place of the condensers, generally used for separating the direct current circuits of the subscribers' lines. The resistances 244, 245 serve, to a certain degree, the same purpose, inasmuch as they prevent a too one sided flow of battery current in case of two lines of very different lengths being connected together, but at the same time they couple the relays 220, 230 together in order to prevent the clearing before both subscribers have replaced their receivers.

If the calling subscriber neglects to take his receiver off before the ringing signal, sent out in position 8 of the switch, is at an end, no more signal is transferred to the other subscriber's line, as is easily understood from the diagram, and as soon as the time relay 200 is released, driving the switch in the position 9, the switch magnet 168 will again receive current by the normally closed contacts 226 and 233 of the relays 220, 230 and the switch arm 223, driving it further to the position 11, in which the release of all the selectors takes place in the same manner as after a finished conversation.

If a conversation has taken place and both subscribers replace their receivers, the relays 220, 230 will simultaneously release their armatures. The switch, standing in position 10 will then receive current, as in the previous case, by the contact 233 of the relay 230 and the switch arm 223, and will go to the position 11. In this position the switch arm 207 has broken the holding circuit of the relay 167 and by its contacts 171, 172, 173 and the switch arms 192, 193, 194 the three phase current from the supply circuit X, Z, Y is closed to the motor for driving the selector back to its normal position. Having reached this position the "off normal" switch 222 is restored to its normal position, breaking the contact 225 and closing the contact 224, thereby sending a current through the switch magnet 168 over the switch arm 223, which drives the switch to its normal position. At the same time the holding circuit of the test relay 139 of the group selector, Fig. 6, is opened by the contact 225, whereby the group selector returns to normal, as described.

The relay 139 of the group selector, Fig. 6,

in opening its three contacts for the adjusting circuit of the motor, in which circuit the relay 116 is included, also opens its contact 153 for holding the relay 84 of the line finder, Fig. 5, but as the relay 116 is arranged for a sluggish release, this relay does not at once close its contact 113. Thus there will be a momentary break in the holding circuit of the relays 84 and 70, causing these relays to return to normal. The line finder is now ready to respond to a new call.

In the description of the operation of the group selector, Fig. 6, it was mentioned, that the selector, when it has found a free trunk line and is going to be stopped, may be brought back nearly three steps, by means of the adjusting current, if it has gone so far past the found line before the motor could be stopped. This is of course a great advantage of this method of adjusting the position of the selector, but if the test brush 126 thus leaves the test contact 129 of the found line for a moment, this line in the meantime does not test busy and in consequence may be taken by another group selector, in which case two calling subscribers will get in on the same trunk line. To prevent this fault, the resistance 163 in the test circuit 162 of the final selector, Fig. 7, may be replaced by a relay 163'—as shown in the lower left corner of the drawing—which, when energized in series with the test relay 139 of the group selector, closes a holding contact 247, by means of which the relay 163 is kept energized until the connector in returning to normal opens the contact 225, thereby for a moment breaking the holding circuit of the relay 163. The minus potential, imposed on the test line 162 over a resistance 248 at the closing of the contact 247 makes the trunk line test busy during the time the test brush 126 leaves the test contact 129.

If a system with first and second group selectors is used, the second group selector may be arranged in the same way as the (first) group selector according to Fig. 6, but if the arrangement for preventing double connection, just described, shall be used, the resistance 110, Fig. 6, should be replaced by a relay 110' closing a holding circuit through a resistance, as shown in the lower left corner of the drawing.

Fig. 8 shows a circuit diagram of a modified arrangement for starting the line finders. The object of this modification is, first, to economize with regard to the number of the line finders required for a certain, large group of subscribers' lines, f. i. 500 or 1000 lines, secondly, to shorten the average time required for a line finder to reach the multiple contacts of a calling line and, thirdly, to reduce the number of line finders started by a calling line. For this purpose a large group of subscribers, f. i. 500 or 1000, have access to every one of a number

of line finders required to take the calls from this group of subscribers, but, as it would be unsuitable to start such a large number of line finders for every call in this 5 large group of lines, the starting is arranged in such a manner that, when a subscriber calls, during normal traffic only those line finders, which happen to be in the neighborhood of the multiple contacts of this 10 subscriber's line, are started.

The field of multiple contacts is divided in sections of for instance 100 lines and for 15 each section is provided a pilot relay 271, connected to the line relays in the same way as the pilot relay 71 in Fig. 5. There is also a secondary pilot relay 274, corresponding to the secondary pilot relay 74 in Fig. 5, but the relay 274 is arranged in a different way, inasmuch as it has its contact 275 not directly 20 connected to a number of individual starting relays of the line finders as in the previous scheme, but connected to a number of sectional contact rails 278, which are joined together, through the winding of a relay 276, 25 provided for each section. The line finders being all common to all the lines of the multiple field, the track of every line finder must cover the whole width of the contact field or panel for the group of lines in question. But 30 for each track the contact rail 278, which transmits the current to the individual starting relay 281 of the line finder, is divided up in as many from each other insulated parts as there are sections of the contact field, and 35 then all the sectional contact rails 278 of one section are joined and connected to the contact 275 of the pilot relay 274, as already mentioned.

The starting relay 281 has its winding on 40 one side connected to the contact 85 of the relay 84, as in Fig. 5, but the other side of the winding—instead of being directly connected to the starting contact of the secondary pilot relay—is connected to one of the contact rails 45 for the three phase current, leading to one of the field coils of the motor. Alternatively the relay 281 may have three windings as shown at the bottom of the drawing, which are all joined and connected to the relay contact 85, on one side, while on the other side they are connected each to one of the three phase contact rails leading to the motor field coils.

The polarizing coil 94 of the motor armature is on one side connected to the neutral point of the field coils 91, 92, 93, as before, but on the other side the coil 94 is connected to an additional contact roller 279, which is in contact with the sectional contact rail 278 60 of the section where the line finder for the moment stands. It will be understood that by means of the sectional contact rails 278, connected vertically together and to the contact 275 of the pilot relay 274, but insulated 65 from the groups of sectional contact rails 278

of all other sections of the contact field, it is possible to limit the starting impulse, sent out by the relay 274, to only starting relays of those line finders, which happen to be standing within the section in question. The sectional contact rails 278 at the same time 70 transmit the battery current for polarizing the armature of the motor.

As an alternative the sectional contact rails 278 may at the same time form the carrying 75 rails for the line finders.

Fig. 8 shows the relays for the sectional contact rails of three consecutive sections, while in the middle section the motor and all the relays for the line finder are shown. 80

The winding of the starting relay 281 has a high resistance so as not to interfere with the three phase current.

The operation of the starting arrangement is as follows:

When a subscriber having his line contacts in the middle section is calling, his line relay will pull up and close the circuit of the pilot relay 271 in the same way as shown in Fig. 5. The pilot relay 271 being energized, 90 sends a current through the middle winding of the secondary pilot relay 274, which closes its contact 275, whereby all the contact rails 278 of this section are connected to earth through the winding of the relay 276, which 95 has a low resistance. The starting relay 281 of every free line finder standing within this section now receives a current on the following path: earth—275—276—278—279—94—91 (92, 93)—281—85—minus pole of battery. This current is very faint, owing to the high resistance of the relay 281, and has no other influence on other parts of the circuit. The relay 281 being energized, closes the three phase current for the field coils 91, 105 92, 93 and the direct current for the armature coil 94 of the motor and sets out plus potential on the test brush through the test relay 82 in exactly the same manner as the starting relay 81 in the previous diagram, Fig. 5. 110 But the direct current from the battery B, Fig. 5, in this case does not flow directly from the plus pole, or earth, to the armature coil 94, but it must go through the low resistance winding of the relay 276 and also pass the 115 contact rail 278 and the contact roller 279. The relay 276 being excited by said current pulls up its armature and opens its contact 277, thereby cutting off an auxiliary starting circuit leading to a winding on each of the 120 two secondary pilot relays of the neighbouring sections. Thus the said auxiliary starting circuit remains inactive. But if the line finder shown in the middle section has moved along its track to some other section, and there 125 is no free line finder standing on any of the contact rails 278 of the middle section, then the relay 276 does not get any current, its contact 277 remains closed and a current flows instead in the auxiliary starting circuit, en- 130

ergizing the secondary pilot relays 274 of both neighbouring sections. These relays now close their contact 275, thereby sending starting current to all free line finders standing within these two sections. These line finders now start to move to the right or to the left, depending on how their direction switch 80, Fig. 5, is standing, and there will always be some of them moving in the direction of the middle section, Fig. 8, where the calling line is to be found. As soon as any one of them enters the middle section its motor armature will receive its current through the winding of the relay 276 of this section which opens its contact 277, thereby withdrawing the "call for assistance" to the neighbouring sections, as will be easily understood from the diagram.

During normal traffic there will always be some free line finders within the section of the calling line, thus this "call for assistance" will be sent to the neighbouring sections only in case of occasional overloads of calls in some section. It is obvious that if, in such a case, it would happen that even in one or both neighbouring sections there are no free line finders, the "call for assistance" will be transferred to the next section or sections by means of the relays 274 and the closed contacts 277 of the "busy" sections. Thus, by means of this starting arrangement it is possible to utilize the line finders in the most economical manner, because any one of all the line finders provided for a large group, for instance 1000 lines, may be used for a call from any line in this large group. At the same time the time for a line finder to find a calling line during normal traffic is reduced and unnecessary wear avoided by starting only line finders which happen to stand near the calling line.

It is well known among telephone engineers that, in most telephone systems, the group selectors may be carried out reversed, that is to say, on the line finder principle. This is of course possible also in the present system and in such a case the above described starting arrangement according to Fig. 8 may be used with advantage for the group selectors as well.

Referring to the group selector and the arrangement of the impulse contacts (130) along the track of the selector, this arrangement in connection with the fact, that the design of the selector is independent of the length of the track, makes it possible to divide the contact field in groups of lines, which are quite different with regard to the number of lines in each group. This is a great advantage, especially in a plant with more exchanges, because the traffic in this case is almost without exception unevenly distributed in the various directions. Thus, in one direction it may be suitable to let the group selector select on such large groups

as 50-60 trunk lines, in order to economize in the total number of trunks required, while in some other direction 10-20 lines may be sufficient to take the total traffic. In the latter case it would evidently be a waste of material to provide multiple contacts for 50-60 lines. In consequence a great deal of material and space is saved by dimensioning the sizes of the groups exactly in accordance with the traffic requirements, which is possible in this system, because the distance between the impulse contacts of the groups is immaterial for the working of the number sender and its control of the group selector. 70

In order to facilitate a change in the number of lines of the various groups even since the plant has been put in traffic, impulse contacts may be provided for each 10 or 20 lines, and these contacts may then be connected or not, according to the size of the groups. 80

Evidently, for the above mentioned reasons it is also possible to subsequently extend the multiple contact field of the group selectors by adding new contact banks, either for taking in new groups of lines or for increasing the number of lines within the groups. 90 In case more than 10 groups of trunk lines shall be arranged for in the group selector, the first digit of the subscriber's number may be a letter, and the first contact segment 95 in the number sender may in this case be made longer so as to take 20 to 25 letters instead of only the ten numerals.

The described telephone system and its various components may of course be modified in many other ways without departing from the features of the invention. 100

I claim:

1. An automatic telephone system having switches in the form of carriages, movable contacts mounted on said carriages, a contact field, a number of tracks for said carriages arranged in front of said contact field, and alternating current motors individually allotted to said switches and mounted on the 105 carriages. 110

2. An automatic telephone system as claimed in claim 1 in which the switches are driven by synchronous motors.

3. An automatic telephone system as claimed in claim 1, in which the switches are driven by synchronous alternating current motors having armatures polarized by means of direct current. 115

4. In an automatic telephone system the combination of a number of switches in the form of carriages, each having an individual electric motor mounted on the carriage and provided with a uniformly movable armature, movable contacts mounted on said carriages, a number of superimposed horizontal tracks for said carriages, a contact field extending vertically on one side of the switches, stationary contact rails extending along the 120 125 130

tracks and means for connecting said movable contacts with said contact rails.

5. A combination as claimed in claim 4 in which the movable contacts are connected with the contact rails by means of electric rollers adapted to engage the rails so as to exert an elastic lateral pressure on both sides thereof.

6. A combination as claimed in claim 4 in which the movable contacts are connected with the contact rails by means of rollers each consisting of two loosely pivoted discs pressed against the opposite sides of the rail so as to form a double contact with partly rubbing and partly rolling contact surfaces.

7. In an automatic telephone system the combination of a number of switches the movable contacts of which are mounted on carriages adapted to run on tracks in front 20 of a contact field and to be driven each by an individual electric motor mounted on the carriage and provided with a uniformly movable armature, and a centrifugal device operated by the movement of the carriage to withdraw the said contacts from the contact field during the movement of the carriage.

8. In an automatic telephone system the combination of a number of switches consisting of carriages adapted to run on tracks 30 in front of a contact field and to be driven each by an individual motor mounted on the carriage and provided with a uniformly movable armature, a number of supply circuits for different currents and means for supplying current from one or the other circuit to the motor to drive the latter at different speeds.

9. A combination as claimed in claim 8 in which the switches are provided with alternating current motors adapted to be driven by alternating currents of different frequency.

10. In an automatic telephone system the combination of a number of switches the movable contacts of which are mounted on carriages arranged to run on tracks in front of a contact field and to be driven each by an individual electrical motor provided with a uniformly movable armature, means for supplying the motors with electrical current for driving purpose, and means for shifting the motor circuit so as to produce a polarization field for centering and holding the armature of the motor in each position of the switch.

11. A combination as claimed in claim 10, in which the motor consists of an alternating current motor the armature of which is provided with a polarizing winding connected at one end to the neutral point of the star connected stator windings of the motor and at the other end through a source of direct current to the neutral point of the star connected windings of an alternating current generator.

12. In an automatic telephone system the combination of a number of switches consisting of carriages arranged to run on tracks in front of a contact field and to be driven each by an individual alternating current motor having a uniformly movable armature, stator and armature windings, a circuit including the stator windings, and a source of alternating current, another circuit including the armature winding and a source of direct current, and means for disconnecting the source of alternating current and switching the stator and armature windings together into a direct current circuit for stopping the movement of the switch. 70

13. A combination as claimed in claim 12, in which a test relay is adapted, upon finding a disengaged line, to disconnect the source of alternating current and to switch the stator and armature windings together into a direct current circuit for stopping the movement of the switch. 75

14. In an automatic telephone system the combination of a number of switches consisting of carriages arranged to run on tracks in front of a contact field and to be driven each by an individual synchronous alternating current motor having a uniformly movable armature one revolution of which corresponds to a number of contact positions of the switch 90 equal to the number of phases used for driving the motor, or a multiple thereof, stator and armature windings, a circuit including the stator windings and a source of alternating phase current, another circuit including the armature winding and a source of direct current, means for disconnecting the source of alternating current and switching the stator and armature windings together into a direct current circuit for stopping the movement of the switch, and a number of polarized relays arranged to work in synchronism with the alternations of the phase currents and to control the said direct current circuit so as to set up, upon said circuit 100 being closed, a field that will cause the armature to be centered and held in a position corresponding to the contact position selected. 105

15. In an automatic telephone system the combination of a number of switches the movable contacts of which are mounted on carriages arranged to run on tracks in front of a contact field, and to be driven each by an individual electrical motor mounted on the carriage, a number sender for controlling the setting of the switches, and stationary contacts provided along the track and adapted to cooperate with one of the movable contacts for sending numerical control impulses back to the number sender. 110

16. A combination as claimed in claim 15, in which the stationary contacts are arranged at irregular distances from one another corresponding to the variable extension of the 115

corresponding groups of line contacts in the contact field.

17. In an automatic telephone system the combination of a number of switches consisting of carriages arranged to run on tracks in front of a field of line and test contacts and to be driven each by an individual electrical motor mounted on the carriage, a number sender for controlling the setting of the switches, stationary contacts provided along the track in positions corresponding to the numerical groups of field contacts, and a contact arm movably mounted on the carriage so as to be able to cooperate with said stationary contacts for sending numerical control impulses back to the number sender during the selection of a group and with the test contacts of the contact field for testing the individual lines.

18. In an automatic telephone system the combination of a number of connectors consisting of carriages arranged to run on tracks in front of a field of line and test contacts and to be driven each by an individual electrical motor mounted on the carriage, a number sender for controlling the setting of the connectors, stationary contacts provided along the track in positions corresponding to the numerical groups of field contacts, and a contact arm movably mounted on the carriage so as to be able firstly to cooperate with said stationary contacts for sending numerical control impulses back to the number sender during the selection of the groups of lines, secondly, to cooperate with the test contacts of the contact field for sending numerical control impulses back to the number sender during the selection of the individual lines, and thirdly, to cooperate with the test contacts of the contact field for the busy test of the line selected.

19. In a combination as claimed in claim 17 the provision of another set of stationary contacts along the track for selecting smaller groups of lines within a selected larger group, one series of stationary contacts being connected to the plus pole and the other to the minus pole of a battery, and a relay being provided for transmitting the impulses to the number sender which relay is connected to the opposite pole of the battery, so as to be energized only by one series of impulse contacts at a time.

20. In a combination as claimed in claim 18 the provision of a relay, which during the selection of an individual line is connected to an intermediate pole of a battery in such a manner, that there will always be a difference of potential between the terminals of said relay when the movable contact arm makes contact with the test contact of a line, whether this line is busy or not, so as to be energized and send a back impulse to the number sender for every subscriber's line passed by the connector.

21. In an automatic telephone system the combination with a number of selective switches of a number sender and means for sending controlling current impulses from the switches back to said number sender, the latter having a spring driven switch arm, mechanically connected with an escapement gear, and sliding on a number of electrically connected contact segments, the contact surface of which may be adjusted to different lengths corresponding to the figures of the recorded number, an electromagnet with a polarized armature being provided for tripping the switch arm, when energized by back impulses in the form of alternations of the current from the central battery, while the armature of the electro-magnet serves as a mechanical brake on the switch arm when the current is broken by the switch arm in leaving a contact segment.

22. In an automatic telephone system the combination with a number of selective switches of a number sender and means for sending controlling current impulses from the switches back to said number sender, the latter having a spring driven switch arm, mechanically connected with an escapement gear, and sliding on a number of electrically connected contact segments, the contact surface of which may be varied to its length, while said tripping gear consists of an electromagnet, having a rotating polarized armature, which is set in rotation by a wheel work and said driving spring when the electromagnet is not energized but will be held by the magnet when energized and allowed to rotate one half turn for every alternation of the current passing the line and the electromagnet.

23. In an automatic telephone system the combination with a number of selective switches of a number sender, means for sending controlling impulses from the switches back to the number sender, and means for converting direct current back impulses sent from the switches into back impulses in the form of alternations of the line current of the number sender, consisting in one of the line branches being connected to an intermediate pole of a central battery, while the other line branch is connected to one of the outer poles of the battery, through a starting relay, but which line branch by the impulse contacts, is intermittently connected to the other outer pole of the battery, whereby the current in the line is reversed.

24. In a combination as claimed in claim 21 the provision of means whereby after the connection has been established, the desired line is called only when the calling subscriber removes his receiver.

25. In an automatic telephone exchange as claimed in claim 1 having line finders without any definite normal position, the combination with a starting relay of a group of

subscribers' lines, of contact rails cut up according to the groups of subscribers, by means of which contact rails the starting impulses are conducted to the individual starting relays of the line finders, so as to start only line finders which happen to stand in the neighbourhood of the multiple field contacts of the calling line, when the traffic is normal, while only in case of overloads line finders standing farther away from the calling line will come into action.

26. In an automatic telephone system as claimed in claim 21, having the grouping of the lines in the contact field of the switches generally carried out on the decade principle, the combination with said system, of a group selector having more than ten sections of multiple contacts, while the corresponding contact segment in the subscriber's number sender is arranged for more than ten steps of the switch arm in order to have the possibility of increasing the capacity of a plant without using more selectors and to reduce the ciphers of the subscriber's number by using letter signs for the longer contact segment of the number sender.

27. In an automatic telephone system as claimed in claim 1 the combination with the automatic ringing device of the connector, of a relay with two windings, one passed by the subscriber's line current from the central battery and the other by the ringing current, these relay windings being connected in such a manner that the influence on the relay of that part of the ringing current which passes through the winding for the battery current, is counteracted by the total ringing current passing through the other winding, so as to prevent the relay from pulling up its armature, before the subscriber closes the battery current by taking off the receiver, the same relay at that moment cutting off the ringing current by opening a normally closed contact.

28. In an automatic telephone system as claimed in claim 1 the combination with the connector of a time relay for delaying the release of the switches for a short time when the desired line is busy, or for sending out the first ringing signal, if the said line is not busy, said relay being energized by a current passing two resistance elements, one of which increases its ohmic resistance by the heating influence of the current, while the other resistance remains practically constant, thus causing its current to be gradually reduced until both currents neutralize their effects on the relay, which in consequence is released thereby causing the desired change in the circuits.
